UNITED STATES PATENT OFFICE.

CARL ALBERT NORDEN, OF CHICAGO, ILLINOIS.

APPARATUS FOR PRESSING TROUSERS.

1,335,013.

Specification of Letters Patent. Patented Mar. 30, 1920.

Application filed March 27, 1919. Serial No. 285,550.

To all whom it may concern:

Be it known that I, CARL ALBERT NORDEN, a citizen of the United States, and a resident of the city of Chicago, county of Cook, and State of Illinois, have invented certain new and useful Improvements in Apparatus for Pressing Trousers, of which the following is a specification.

My invention relates to an improvement in apparatus for pressing trousers, and has for its object the provision of such a device which is simple in construction and easy to operate.

A further object is the provision of a trouser-pressing apparatus which is adapted to be folded upon itself, and which will serve to press the trousers without the application of heat.

Other objects will appear hereinafter. The invention consists in the combinations and arrangements of parts hereinafter described and claimed.

The invention will be best understood by reference to the accompanying drawings forming a part of this specification, and in which,

Figure 1, represents a perspective view of the device in operation, partly in section,

Figs. 2 and 3, represent fibrous elements used in the device,

Fig. 4, a section taken on line 4—4 of Fig. 1,

Fig. 5, shows the device in its folded condition, and

Fig. 6, represents a fragmental sectional view on lines 6—6 of Fig. 5.

The device, which is made preferably of wood, consists of tapering sections 7 of increasing proportions, having spacing elements 8 interposed between their adjacent ends, to the lateral sides of which the adjacent ends of elements 7 are hinged by a suitable flexible element 9, such as leather or canvas. Hinged on the opposite lateral edges of members 7, by a suitable flexible element 11, such as leather or canvas, are elements 10 which form leaves on said members 7, said elements 10 being adapted to fold upon one face of the members 7. Sealed to one of the leaves in each section is a latch 12 pivoted at one end and having at its opposite end an arcuate slot 13. Project-

ing from the coöperating leaf in the same section is a stud 14, which is adapted to coöperate with the arcuate slot 13 in the latch 12, thereby securely binding the leaves 10 in closed position upon the element 7. The slot 13 is made arcuate in form, for the reason that the outer end of the slot will engage the element 14, and upon pressing the latch 12 down the members 10 will be drawn closer to each other.

Secured on the faces of elements 10, transversely and adjacent the ends thereof, are reinforcing elements 15 which serve to prevent warping or flexing of the elements 10 while in operative position. As clearly shown in Fig. 1, the terminal leaves 10, or those at the lower end of the device, are cut shorter than the coöperating section 7. Secured adjacent the lower edge of said terminal leaves 10 is a reinforcing member 16 which projects beyond the lower end of said leaves. The purpose of so constructing the terminal or lower leaves of the device is to allow greater space between said leaves 10 and the coöperating section, at the lower end thereof. By so constructing the device, the space which is filled by the cuff of the trousers is made greater than the remaining space which is filled by the rest of the trousers to be pressed.

In operation, the leaves 10 are opened flat, leaving the elements 7 exposed and free to receive, on their inner surfaces, the object to be pressed. A fibrous element 17, constructed in one piece, is then laid upon the elements 7 so as to cover the same. One of the legs of the trousers to be pressed is then laid upon the fibrous element 17, with the cuff of the trousers at the lower or smaller end of the device. The leg of the trousers is then brushed out smooth, so as to be in proper condition for pressing. A second fibrous element 17 is then laid upon this trouser leg, and the second leg of the trousers is positioned over this second fibrous element and smoothed out, ready for pressing, similar to the first leg. A third fibrous element 17 is then positioned over the second leg and the leaves 10 are folded upon the trousers and securely fastened by means of the latch 12 coöperating with the stud 14. The leaves 10 are so hinged to the

elements 7 so as to leave, when said leaves are folded upon said elements 7, very little space between these elements. Consequently, when a pair of trousers is inserted 5 between the leaves 10 and the elements 7, as already described, the leaves 10 coöperating with the elements 7 will act as a clamp and serve to press down tightly upon the trousers disposed between these elements. 10 By leaving the trousers so disposed and so clamped between these elements for a short time will result in having the trousers neatly pressed and well creased, as will be readily understood. The purpose of the elements 15 17 is to prevent the fabric from coming into contact with the wood, and thereby prevent the device from impressing upon the trousers to be pressed the grain or inequalities of the wood. The device is constructed in 20 sections hinged together, as already described, for the purpose of allowing the same to be folded, the terminal members 10 folding upon the central member 10. In folding the device, the spacing elements 8 retain 25 the elements 10 at their adjacent ends in spaced relation to each other, so that the trousers held within the device bend in a circular shape at the juncture of these sections, and thus no crease or wrinkle appears in the 30 trousers being pressed, no matter how long the same may be in the device while it is in its folded position. This is clearly shown in Fig. 6.

It will also be noted in Fig. 6 that the 35 leaves 10, at their ends, project beyond the corresponding ends of the coöperating elements 7. This distance which the ends of the leaves 10 project beyond the corresponding ends of the coöperating elements 7 is 40 equal to one-half the width of the spacing elements 8, so that upon being straightened out the device will present a continuous surface on both sides, the projecting ends of the adjacent leaves 10 engaging with each 45 other at the central longitudinal line of the element 8. Provided at the lower end of the device, in the terminal member 17, is an opening or hole 18 by which the device is adapted to be hung up.

50 With a device such as I have described it is possible, without the application of any heat, to neatly and efficiently press a pair of trousers in a very short time. By this device there is also provided a means for hanging up a pair of trousers and retaining the same in a well pressed condition, so that upon the owner's wishing to use the trousers which have been hung away he will find them in a well pressed condition, free from wrinkles.

60 Another feature of the device is that it provides a means for folding a pair of trousers, and at the same time retaining the trousers in a perfectly pressed condition. This device is especially useful to one traveling, as the trousers may be positioned within 65

the device as above described, and the device may be folded and placed within a suit-case or hand bag. In this respect the utility of such a device is readily apparent.

Having described my invention, what I 70 claim as new and desire to secure by Letters Patent is:—

1. A trouser pressing apparatus adapted to be folded upon itself, comprising a plurality of sections; and spacing means interposed between the adjacent ends of said sections, substantially as described. 75

2. A trouser pressing apparatus adapted to be folded upon itself, comprising a plurality of sections; spacing means interposed 80 between the adjacent ends of said sections; and leaves hinged opposite each other to the lateral edges of said sections and adapted to be folded upon said sections, substantially as described. 85

3. A trouser pressing apparatus adapted to be folded upon itself, comprising a plurality of sections; and leaves hinged opposite each other to the lateral edges of said 90 sections and adapted to open outwardly from said sections, substantially as described.

4. A trouser pressing apparatus comprising a plurality of sections; and a spacing element between the adjacent ends of said 95 sections, substantially as described.

5. A trouser pressing apparatus comprising a plurality of sections; leaves hinged opposite each other to the lateral edges of said sections and adapted to close upon their 100 respective sections; and reinforcing members arranged transversely of and adjacent the ends of said leaves, substantially as described.

6. A trouser pressing apparatus comprising a plurality of sections; leaves hinged opposite each other to the lateral edges of said sections and adapted to close upon their respective sections; and reinforcing members arranged transversely of and adjacent 110 the ends of said leaves, the ends of said leaves projecting beyond the corresponding ends of the sections to which hinged, substantially as described. 105

7. A trouser pressing apparatus comprising a plurality of sections; spacing members interposed between the adjacent ends of said sections; and means for connecting said sections to said spacing members, substantially 115 as described.

8. A trouser pressing apparatus comprising a plurality of sections; spacing members interposed between the adjacent ends of said sections; and flexible means for connecting said sections to said spacing members, substantially as described. 125

9. A trouser pressing apparatus comprising a plurality of sections; leaves hinged, opposite to each other, to the lateral edges of said sections and adapted to close upon 130

said sections, the leaves secured to one terminal section being arranged to permit said section to project beyond the terminal end of said leaf; and reinforcing members secured to and projecting beyond the said end of said terminal leaf, substantially as described.

In testimony whereof I have signed my name to this specification in the presence of two subscribing witnesses.

CARL ALBERT NORDEN.
